THERMOSTATIC FITTING

Parke H. Thompson, II, Maplewood, Mo., assignor to Alco Valve Company, Inc., St. Louis, Mo., a corporation of Missouri

Application November 21, 1935, Serial No. 50,991

7 Claims. (Cl. 297—3)

This invention relates to thermostatic fittings of general applicability, but especially designed to be intercalated in refrigerant-carrying conduits, and corresponding to the temperature of the refrigerant within the conduit.

Prior to the advent of the present invention, some manufacturers of mechanical refrigerators have been content to merely place the thermostat in the refrigerated chamber, where it responds to the temperature of the refrigerated atmosphere. Others have effected a compromise by clamping the thermostat against the refrigerant conduit, so that it responds to the composite temperature of the refrigerant and the atmosphere of the refrigerated chamber, but the placing of the thermostatic element in either of these locations is unsatisfactory, for it responds to spurious conditions, such as caused by the momentary opening of the refrigerator door.

It has been proposed to enclose the thermostatic bulb within the refrigerant conduit, but the means for doing so, up to the present time, have been difficult or expensive to construct and install, or have formed an obstacle to the normal flow of the refrigerant.

The general object of the present invention is to provide a fitting, either of straight or bent form, adapted to be interposed between the adjacent ends of a refrigerant conduit so as to form part of the said conduit, and enclosing as a unitary part thereof, a thermostatic bulb spaced from the walls of said fitting and having an end construction which minimizes its obstruction to the flow of refrigerant through the conduit.

Another object of the invention is to provide a fitting having a thermostatic bulb arranged therein and supported laterally from the walls of said fitting.

A further object of the invention is the provision in a thermostatic fitting, as described, of lateral posts supporting the bulb, the posts being hollow so that one can form a portion of the tube which places the bulb in communication with the control element of the thermostat, while the other post may be utilized for filling the bulb and its appurtenant instrumentalities with the volatile fluid.

Still another object of the invention is to streamline the ends of the bulb so that the flowing refrigerant does not create eddies and back pressure at the forward end of the bulb, and causing the refrigerant to follow the surface of the bulb to its rearward end, making the thermostat extremely sensitive to the temperature of the flowing refrigerant.

A further object of the invention, in connection with that form in which the bulb follows the bend of a fitting, is to position the bulb so that its surface will be angularly impinged by the flowing refrigerant, thereby scouring away any surface film of inert refrigerant which ordinarily would cling to the bulb.

Another object of the invention is to locate the bulb in the conduit closer to the bottom wall than to the other walls, so that it will be bathed in a stratum of the denser gas.

Other objects of the invention will appear as the following description of a preferred and practical embodiment thereof proceeds.

In the drawing, throughout the several figures of which the same characters of reference have been employed to designate identical parts:

Figure 1 is a longitudinal diametrical section through a straight fitting embodying the principles of the present invention;

Figure 2 is a cross section taken along the line 2—2 of Figure 1;

Figure 3 is a longitudinal diametrical section through an elbow-shaped fitting;

Figure 4 is a vertical axial section taken at right angles to the view shown in Figure 3, the lower portion being broken away;

Figure 5 is a cross section similar to that of Figure 2, but showing a slightly modified form of the invention; and

Figure 6 is a cross section taken along the line 6—6 of Figure 1.

Referring now in detail to the several figures, and first adverting to that form of the invention illustrated in Figures 1 and 2, the fitting 1 is constituted by standard end connections 2 and 3, which may be similar and, as shown, are threaded and of the solderless type, it being understood of course that the construction of the connections as shown is exemplary only and that any other form may be employed without transcending the scope of the invention.

Said connections are provided at either inner end with annular rabbets 4 and 5, constituting a seat for the ends of the cylindrical section or barrel 6, which cylindrical section is preferably soldered to the end connections as is indicated at 7.

The end connections are bored as at 8, so as to make the fitting a continuation of the refrigerant or other conduit in which the fitting is intercalated. The diameter of the intermediate section or barrel 6 is larger than the diameter of the bores 8.

Within the barrel 6 is a thermostatic bulb or

capsule 9. This was inserted into the barrel 6 before the latter was secured to the end connections 2 and 3, and secured in place within said barrel by means of posts 10 and 11, which pass laterally from the interior of said barrel to the exterior through apertures 12 and 13 formed in a wall of the barrel. The posts are suitably secured to the wall of the barrel 6 by solder or any other suitable means. The posts 10 and 11 are preferably hollow, and one of the posts, for example, the post 10, forms a continuation on the outside of barrel of the tube 14 which leads to the expansible motor, not shown, actuated by the thermostatic element.

The thermal insulation of the bulb 9 is assisted by making the posts of metal of low conductivity and by restricting their cross section to the minimum area so as to reduce the rate of heat exchange with the metal of the enveloping conduit to a minimum. Since it may be desirable to provide auxiliary support for posts of such restricted cross section, filler pieces 25, see Figure 1, may be provided surrounding the posts 10 and 11 and against which the tube 9 rests. The filler pieces are preferably of non-conductive material such as a phenolic condensation product and they may be streamlined in the direction of flow through the conduit, as indicated at 26 in Figure 6.

The wall of the tube 9 is preferably made as thin as possible so as to obviate any substantial metallic reservoir of latent heat which would retard the response of the thermostat to temperature changes of the fluid within the conduit.

The tube 11 also may be hollow and serves as a means of filling the thermostatic capsule with volatile fluid. Upon completion of the filling operation, the post 11 is permanently sealed off.

It will be observed in Figure 1 that the opposite ends of the bulb 9 are tapered, coming substantially to a point at 15. The ends of the bulb may thus be described as streamlined, which shape operates to cleave the flowing refrigerant gas so as to prevent eddies and back pressure against the anterior end of the bulb 9. The gas thus cleft flows with substantially undiminished velocity, through the annular space 16, between the bulb 9 and the inner surface of the barrel 6, and exits from the fitting by way of the end connection 3. The posterior end of the bulb 9 is streamlined so as to direct the flowing gas down close to the surface of the thermostat in the rear, thereby making the bulb substantially one hundred percent efficient in its response to temperature variations of the refrigerant.

Figures 3 and 4 show an elbow fitting adapted to be interposed between adjacent ends of a refrigerant conduit and to form a bend in said conduit. In this form of the invention, the end connections 2 and 3 are the same as in that form of the invention first described. The barrel 21, as shown, has the form of a long sweeping right-angled curve or elbow. It is soldered to the end connections in the same manner as in Figure 1, and the bulb is likewise streamlined at the ends. The bulb is supported away from the sides of the barrel 21 by the hollow posts 10 and 11 which extend laterally through the side wall of the fitting. The posts lead respectively to the tube 10 which serves the expansible element, not shown, and to a filling source, not shown, by means of which the bulb 18 is charged with volatile fluid, after which the tube 11 is sealed off.

The form of the invention illustrated in Figure 3 has the advantage that the surface of the bulb 18 is disposed at an angle to the direction of the in-

coming gas, so that the gas impinges at an angle upon the surface of said bulb, in the zone indicated by the brace 17, scouring this portion of the bulb 18 thoroughly and removing the inert gaseous refrigerant which would ordinarily cling to the bulb 18 through skin film. This makes the bulb extremely quick in its response to the changes in temperature in the flowing refrigerant.

It is obvious that in constructing that form of the invention shown in Figure 3, the bulb 18, together with the posts 10 and 11 are made sufficiently short to pass into the barrel 21, are introduced into said barrel and the posts aligned with apertures suitably placed in the wall of said barrel and then pushed slightly so as to extend through to the outside of said barrel where the post 10 is then connected so as to form part of the tube 24. After the bulb 18 has been filled, the post 11 may be sealed off by pinching it together or by soldering, or in any other suitable manner.

Figure 5 shows a slight variant of the invention applicable either to the straight or bent type fitting, in which the bulb 19 is eccentrically mounted within the barrel 20, so as to lie closer to the bottom wall of the said barrel than to the other walls. In this position, it is bathed by the stratum of the denser gas passing through the conduit.

It is obvious that the above invention realizes the construction of a thermostatic fitting which is simple and inexpensive to construct, easily installed, and which offers the minimum of resistance to the flow of the refrigerant gas through the conduit in which it is interposed. It will be understood to those skilled in the art that the specific details of construction and the arrangements of the parts as herein disclosed and described is merely by way of example and not to be construed as limiting the scope of the invention as claimed.

What I claim is:

1. Thermostatic fitting comprising an open ended tube, nipples at the ends of said tube and connected thereto, said nipples being threaded for connection to a conduit, a thermostatic bulb in said tube, posts extending through a wall of said tube in longitudinally spaced relation supporting said bulb adjacent its ends in spaced relation to the wall of said tube, said posts being hollow and communicating with said bulb, one of said posts communicating externally of said fitting with an expansible actuator operated by said thermostatic bulb and the other being sealed having served as a means for charging volatile fluid into said bulb.

2. Thermostatic fitting comprising a conduit, a thermostatic bulb in said conduit, a hollow post supporting said bulb in spaced relation to said conduit, the material of said post being of minimum cross sectional area to throttle the exchange of heat through its metallic mass, and auxiliary supporting means comprising spacing pieces of thermally non-conductive material surrounding said post and engaging said bulb and conduit.

3. Thermostatic fitting comprising an open ended tube, nipples at the ends of said tube and connected thereto, said nipples being adapted for connection to a conduit, a thermostatic bulb extending longitudinally in said tube, having wedge-shaped ends confronting the bores of said nipples, posts extending through a wall of said tube in longitudinal spaced relation supporting

said bulb adjacent its ends in spaced relation to the wall of said tube, said posts being hollow and communicating with said bulb, one of said posts communicating externally of said fitting with an 5 expansible actuator operated by said thermostat, and the other being sealed, having served as a means for charging volatile fluid into said bulb.

4. Thermostatic fitting comprising an open ended tube, nipples at the ends of said tube and 10 connected thereto, said nipples being adapted for connection to a conduit, a thermostatic bulb in said tube, said tube and bulb being curvilinear about a common center, posts extending through a wall of said tube in longitudinally spaced relation 15 supporting said bulb adjacent its ends in spaced relation to the wall of said tube, said posts being hollow and communicating with said bulb, one of said posts communicating externally of said fitting with an expansible actuator 20 operated by said thermostat, and the other being sealed, having served as a means for charging volatile fluid into said bulb.

5. Thermostatic fitting as claimed in claim 4,

said bulb having wedge-shaped ends confronting the bores of said nipples.

6. Thermostatic fitting comprising a conduit, a thermostatic bulb in said conduit spaced from the walls thereof, a tube communicating with said 5 bulb and adapted to lead fluid under pressure therefrom to a thermostatically controlled device, and an element made of thermally non-conductive material surrounding said tube and supporting said bulb in heat insulating relation to the metallic mass of said fitting.

7. Thermostatic fitting comprising an open ended tube, a thermostatic bulb in said tube, 10 posts extending through a wall of said tube in longitudinally spaced relation supporting said 15 bulb adjacent its ends in spaced relation to the wall of said tube, said posts being hollow and communicating with said bulb, one of said posts communicating externally of said fitting with an expansible actuator operated by said thermostatic bulb and the other being sealed, having 20 served as a means for charging volatile fluid into said bulb.
